UNITED STATES PATENT OFFICE.

LEE O. BARNES, OF PORTLAND, OREGON.

ARTICLE-RECEPTACLE.

1,116,210.

Specification of Letters Patent.

Patented Nov. 3, 1914.

Application filed December 27, 1913. Serial No. 809,067.

To all whom it may concern:

Be it known that I, LEE O. BARNES, citizen of the United States, residing at Portland, in the county of Multnomah and State 5 of Oregon, have invented certain new and useful Improvements in Article-Receptacles, of which the following is a specification.

This invention relates to an improved article receptacle, and the primary object 10 thereof is to provide means in the nature of an automatic door of the turn-style type whereby various commodities, for instance, milk bottles, may be delivered to the interior of the said receptacle and there safely 15 housed until purposely removed by the authorized party having access thereto.

The above and additional objects are accomplished by such means as are illustrated in their preferred embodiment in the accompanying drawings, described in the following specification and then more particularly pointed out in the claims which are appended hereto and form a part of this application.

25 In describing my invention in detail reference will be had to the accompanying drawings wherein like characters denote like or corresponding parts throughout the several views, and in which:—

30 Figure 1 is a longitudinal sectional view of a device constructed in accordance with the present invention; and Fig. 2 is a top plan view of the device, partly broken away.

Before proceeding with the description 35 of the drawings, I desire to call particular attention to the fact that while I have evolved my invention with particular reference to its application as a milk bottle receptacle, the same may be readily utilized 40 as a receptacle for various commodities or articles of general merchandise.

Referring now to the drawings wherein is illustrated the preferred embodiment of my invention the numeral 1 designates a suitable supporting structure to which the receptacle, designated as an entirety by the 45 numeral 2 is secured in any suitable manner, preferably as indicated at 3 in the drawings. The said receptacle comprises the

50 usual top 4, bottom 5 and sides 6, the said top and bottom, as is illustrated to advantage in Fig. 2 of the drawings, extending at one end of the receptacle, beyond the extremity of the sides 6 to effect, according 55 to the position of the receptacle, a suitable platform designated 7. One end of the re-

ceptacle is provided with a door 8 hinged as at 9, whereby access to the interior of the receptacle may be had, the said door 8 being normally closed and locked in such closed position through the medium of a suitable lock designated 10. At the opposite end 60 of the receptacle, and at a point adjacent the plane of the side extremities, I provide an automatic door of the turn-style type, the 65 same comprising a vertical shaft 10', the extremities of which are journaled within bearings provided therefor at the top and bottom thereof. Arranged over the said shaft 10' and extending from the top to the 70 bottom of the receptacle, I provide a sleeve 11 having formed integrally therewith, blades or rings 12 arranged, preferably, in spaced relation and in radial relation to the vertical axis of the said door. In the 75 preferred form of the invention four wings are provided, the same being arranged in pairs, one pair of wings extending transversely to the other, the said wings during rotation of the door being adapted for engagement with the sides 6 of the receptacle 80 to at all times close what would otherwise be the open end thereof.

The structure or construction of the device having been described, it now remains 85 to recite the operation thereof. When it is desired that a milk bottle or other article be delivered to the interior of the receptacle, the said article is first placed upon the platform 7 between the wings of the turn-style 90 door, whereupon the said door is manually rotated, causing the article to be delivered to the interior of the receptacle, the said article, by reason of its engagement with one of the wings 12, being forced from the 95 path of rotation of the said door as is clearly indicated by the dotted lines in Figs. 1 and 2 of the drawings. Any number of articles may be delivered to the interior of the receptacle in the manner above described. After delivery, a removal of the 100 said articles can only be effected by the authorized party having access to the interior of the receptacle through the opening, normally closed by the hinged door 8.

In actual practice, when used in the following capacity, an empty bottle may be so placed against the wings of the receptacle from the interior thereof, as to be automatically delivered to the platform 7 simultaneously with the delivery of a full bottle to the interior of the receptacle.

From the above, taken in connection with the accompanying drawings, it is apparent that should the article acted upon, for any reason fail to move out of the path of the door, a continued rotation of the door would be rendered impossible, as one of the wings thereof would bind the said article against the side of the receptacle, thereby preventing the removal of the article other than from the interior of the device; that the said door effects a barrier against access to the interior of the receptacle at all times; and that a theft, or removal of an article, after having once been delivered to the interior of the receptacle, cannot be effected other than by duly authorized parties.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. An article receptacle including a horizontally disposed box like structure, a shaft having its ends journaled in the top and bottom of said structure, and means upon said shaft engageable respectively with the top, bottom and sides of the structure, said

means being rotatable to deliver articles resting upon the bottom of the structure into the interior thereof, as and for the purpose set forth.

2. An article receptacle including a horizontally disposed box like structure, a shaft having its ends journaled in the top and bottom of said structure, said shaft being disposed adjacent one end of the structure, a revolving door mounted upon said shaft, said door being engageable respectively with the top, bottom and sides of said structure, said revolving door forming a closure for one end of the receptacle, a hinge door forming a closure for the opposite end of the receptacle, said revolving door being actuatable to deliver articles resting upon the bottom of the structure into the interior thereof, as and for the purpose set forth.

3. In an article receptacle, a door hinged at one end of said receptacle, said door adapted to normally close access to the interior of said receptacle, a vertical shaft operable within the receptacle at a point adjacent the opposite end thereof, a sleeve rotatable with said shaft, wings radiating from said sleeve, the said wings adapted to engage the top, bottom and sides of the said receptacle and to engage the article acted upon to deliver the said article to the interior of the said receptacle by rotation of said shaft.

In testimony whereof I affix my signature in presence of two witnesses.

LEE O. BARNES.
